Charles T. Foot, of Bristol, Conn.
Letters Patent No. 1162. Dated Nov. 1, 1859.

Number
1162

The schedule referred to in these Letters Patent and making part of the same.

To all whom it may concern:

Be it known that I, Charles T. Foot, of Bristol, County of

Dec 11/62

Hartford and State of Connecticut, have invented or produced a new and original Design for Clock Cases, and I do hereby declare that the following is a full and exact description of the same:

In the accompanying Photographic views is shown a new and original Design for a Clock Case.

A. is the oval gothic shape Case.

B. a square shape pedestal, or Base,

C. the oval gothic shape, rounded face band,

D. is the oval gothic shape sash door,

E. is the oval gothic shape ornamented face glass.

The whole combined to produce a plain and rich Design for a Clock Case.

What I claim therefore and desire to secure by Letters Patent

End is the design for a Clock Case as herein above, illustrated and set forth.
